UNITED STATES PATENT OFFICE

FRED HIRSH, OF NEW YORK, N. Y., ASSIGNOR TO ADJUSTA COMPANY, A CORPORATION OF NEW YORK

DESIGN FOR AN APPAREL BUCKLE

Application filed January 9, 1932. Serial No. 42,439. Term of patent 7 years.

To all whom it may concern:

Be it known that I, FRED HIRSH, a citizen of the United States, residing in the city of New York, in the county of New York and State of New York, have invented a new, original, and ornamental Design for Apparel Buckle, of which the following is a specification, reference being had to the accompanying drawings, forming part thereof.

The design relates particularly to the frame of buckle.

I claim:

The ornamental design for an apparel buckle as shown and described.

FRED HIRSH.
